CLAIM

The ornamental design for a canister for collecting wound exudate, as shown and described.

DESCRIPTION

FIG. 1 is a top, front, and right side perspective view of a canister for collecting wound exudate showing our new design.

FIG. 2 is a bottom, rear, and left side perspective view thereof.

FIG. 3 is a top plan view thereof.

FIG. 4 is a bottom plan view thereof.

FIG. 5 is a right side view thereof.

FIG. 6 is a left side view thereof.

FIG. 7 is a front view thereof; and,

FIG. 8 is a rear view thereof.

The broken lines represent portions of the canister for collecting wound exudate that form no part of the claimed design.

1 Claim, 5 Drawing Sheets

Related U.S. Application Data

a division of application No. 29/492,114, filed on May 28, 2014, now Pat. No. Des. 764,653.
